UNITED STATES PATENT OFFICE

FREDERICK WILLIAM COEN, OF LOS ANGELES, CALIFORNIA.

VALVE FOR INTERNAL-COMBUSTION ENGINES.

1,068,567.

Specification of Letters Patent.

Patented July 29, 1913

Application filed March 27, 1912. Serial No. 686,638.

To all whom it may concern:

Be it known that I, FREDERICK WILLIAM COEN, a citizen of the United States, residing at Los Angeles, in the county of Los Angeles, State of California, have invented a new and useful Valve for Internal-Combustion Engines, of which the following is a specification.

This invention relates to valves for controlling the admission and exhaust of internal combustion engines, particularly those operating on a four-stroke cycle.

The main object of the invention is to provide a valve for the stated purpose which will open and close the ports by sliding motion, and which will automatically take up any wear so as to always provide a tight closure.

A further object of the invention is to provide for simplifying the construction and operation of the valve with a four-stroke cycle engine by causing one member of the valve to have a drag or frictionally resisted movement relative to the other, whereby a different operation of the valve is secured on different strokes without the necessity of special mechanism for that purpose.

Other objects of the invention will appear hereinafter.

30 The accompanying drawings illustrate an embodiment of the invention, and referring thereto—

Figure 1 is a plan of the valve. Fig. 2 is a vertical section of the upper portion of 35 the cylinder showing the valve therein, the valve operating mechanism being shown in elevation. Fig. 3 is a horizontal section on line x^3-x^3 . Fig. 2. Fig. 4 is a section on line x^4-x^4 in Fig. 3. Fig. 5 is a section on line 40 x^5-x^5 showing an automatic governor for disconnecting the valve when the speed is excessive.

1 designates a cylinder which is provided in its head 2 with inlet ports 3 and outlet 45 ports 4, said ports communicating respectively with the inlet and exhaust chambers 5 and 6, inlet chamber 5 communicating with the usual means for supplying mixture, and exhaust chamber 6 communicating with the 50 outer air or exhaust pipe. An oscillatory valve member 8, formed as a flat disk, rests against the top of the cylinder on the inside thereof and is carried by a tubular valve stem 9 extending through a bore 10 in the 55 top or head of the cylinder, said stem being

provided at its upper end with an arm 12 connected to a suitable operating means hereinafter described. Another valve disk 13 is carried by a central valve shaft or stem 15 extending within the tubular valve stem 60 9 aforesaid, said central valve rod or stem being provided with a collar 16 engaged by a spring 17 which rests on the outer valve stem 9 so as to tend to press the lower valve disk 13 upwardly against the upper valve 65 disk and hold said valve disks in frictional contact, whereby any rotative movement imparted to the upper valve disk by rotation of its stem tends to drag the lower valve disk around in the same direction. 70

A stop means is provided for limiting the angular movement of the lower valve disk consisting, for example, of a bracket 20 mounted on the cylinder head and provided with a rectangular slot 21 through which 75 extends the upper end of the inner valve shaft 15, said end of the inner valve shaft being formed, for example, in diamond-shape, as shown at 22, so as to permit it to turn to a limited extent in either direction 80 within the slot 21.

Oscillatory movement of the arm 12 is produced, for example, by means of a link 23 connected to said arm and to a crank 24 on a shaft 25 which is operated by any suitable means, such as spiral gears 26 and 27 from the main shaft 28 so as to turn at one-half the speed of the main shaft. 85

In case it is desired to provide governor means for controlling the operation of the valve, the construction shown more particularly in Fig. 5 may conveniently be used, the arm 12 carrying a pendulum 30 having a weight 31 at its outer end and being provided with an arm 32 having a pawl or dog 33 adapted to engage within a notch 34 in the outer valve shaft 9, a spring 35 connecting the said arm 32 to the outer shaft 9 and tending to draw and hold said pawl in said notch. The arm 12 in this case is rotatable 100 on the outer shaft 9, its movement, however, being limited by a key 36 on said arm engaging in an arc-shaped slot 37 in the outer shaft.

The lower or inner valve disk 13 is provided with wide ports 40 on the exhaust side and with relatively narrow ports 41 on the inlet side. The other valve disk 8 is provided with relatively narrow ports 43 and 44 on the inlet and outlet sides. The posi- 110

tion shown in Fig. 3 is that in which the valve disks are moving in the direction of the arrow and are just beginning to open the inlet ports 3 to communication through the ports 43 in the upper disk; the ports 41 in the lower disk being at this time in register with the ports 43, and the lower disk being carried around by friction with the upper disk so that in this movement the inlet port is opened. During this movement the ports 44 on the other side are moving away from the exhaust ports 4 so that the exhaust is closed. At a certain point of this movement of the upper disk corresponding to the termination of the intake stroke, the movement of the lower disk is arrested by the stop means 22, 21 and the continued movement of the upper disk closes the inlet opening by moving past the stationary ports 3, this movement corresponding to the compression stroke. As the disk 8 begins its return movement in the opposite direction to that shown in the arrow, the disk 13 at first moves with it so that the conditions remain the same as they were in the preceding stroke, namely, closing the inlet opening, this corresponding to the explosion stroke. In the latter half of this opposite rotation of the disk 8 the movement of the disk 13 is arrested so that the ports 43 and 41 are again brought into register, but during this portion of the stroke the ports 43 are moving beneath the closed portion of the cylinder head, having passed the ports 3. At the same time the ports 44 on the other side are moving beneath the fixed ports 4, thereby opening exhaust connection, ports 40 at that side, in the lower disk being of sufficient width to always provide free communication when the ports 44 and 4 are in register, valve disk 13 being extended to that side for the purpose of balance.

What I claim is:

1. A valve for gas engines, comprising, in combination with a casing, two disks rotatably mounted therein and in contact with each other, a shaft connected to one of said disks, means for oscillating said shaft and the disk connected thereto and means for pressing the other disk against said operated disk so as to be dragged therewith in either direction, said casing and disks having ports for registering with one another to open communication through the valve, the ports in the operated disk being closed by the other disk when the latter is dragged in one direction, and opened thereby when it is dragged in the other direction.

2. A valve for gas engines, comprising, in combination with the cylinder casing, two disks rotatably mounted in the end of said casing, a tubular shaft connected to one of said disks, means for oscillating said shaft and the disk connected thereto, means for pressing the other disk into contact with the operated disk so as to be dragged therewith, means for limiting the relative angular movement of said second mentioned disk, the end of the cylinder and said disks being provided with ports for registering with one another to open communication through the valve, and the ports in the operated disk being closed by the dragged disk when the latter is dragged in one direction and opened thereby when the latter is dragged in the other direction.

In testimony whereof, I have hereunto set my hand at Los Angeles, California, this 19th day of March, 1912.

FREDERICK WILLIAM COEN.

In presence of—

ARTHUR P. KNIGHT,
F. A. CRANDALL.
